RADIATOR RIBBON FORMING MACHINE

Stanislaus Przyborowski, Tonawanda, N. Y., assignor to Fedders Manufacturing Company, Inc., Buffalo, N. Y.

Application May 1, 1939, Serial No. 271,041

8 Claims. (Cl. 113—1)

This invention relates to a machine for forming joints in radiator ribbons. In preparing the ribbon elements of a cellular radiator core for final assembly, it has heretofore been deemed necessary to perform the several joint forming operations in manually controlled and operated bending fixtures. This practice has not only curtailed effective production, but has caused occasional damage to the ribbons because of the difficulties of handling repeatedly these relatively fragile elements. In smaller cores, such as those in automobile heaters, these difficulties have been increased, because the short strips of ribbon cannot be handled and formed without interfering with the bending mechanisms.

In the present machine it is proposed to form the ribbon joint structures simultaneously, and with the aid of automatically operated fixtures, thus eliminating the dangers of several manual handlings, and the uncertainties of human supervision. The machine is additionally devised for a wide range of adjustment, so that ribbons of any length may be formed with equal effectiveness.

The present invention moreover provides for the combination, with the necessary ribbon folding, holding, and die means, of control and safety mechanism for insuring the operation of the machine elements in a proper sequential order, thereby making it possible to form the complete ribbon in one machine, and substantially as one operation. Other features and advantages will become apparent as this description of a typical embodiment proceeds, reference being made to the accompanying drawings, wherein:

Fig. 1 is a perspective view of a radiator ribbon in its pre-formed state;

Fig. 2 is a side view of the ribbon after it is bent and joined in the present machine;

Fig. 3 is an enlarged fragmentary cross section taken through the interlocking joint of the ribbon;

Fig. 4 is a longitudinal section through the machine;

Figs. 5, 6, 7, and 8 are enlarged cross sections taken on the lines 5—5, 6—6, 7—7, and 8—8 of Fig. 1. In several of these views, the mechanisms which would have appeared in the background have been omitted, to prevent confusion;

Fig. 9 is a section on the line 9—9 of Fig. 7;

Figs. 10, 11, and 12 are enlarged longitudinal sections through the die units of the machine, showing the progressive bending operations;

Fig. 13 is an enlarged fragmentary section on the line 13—13 of Fig. 5.

A typical water tube ribbon R is shown in Fig. 1, where it will be observed that it is originally supplied in straight lengths having corrugations 19 and flattened extremities 21 and 31. After undergoing the forming operation in the present machine, the ribbon appears as a water tube section or "outer," as shown in Fig. 2, where it is folded centrally to form two parallel legs 20 and 30, connected at their free extremities 21 and 31 in an interlocking joint O. In the formation of the joint O (Fig. 3), sections 23, 33 of the extremities 21 and 31 are bent laterally inward, and their terminals 24, 34 are bent back in mutual interlocking engagement.

The median or folded portion of the ribbon constitutes what is termed the closed end header C, and it will be observed that the corrugations 19a, originally formed thereon, are flattened as indicated by the numerals 25, 35, to present a substantially planar surface. For additional purposes of identification, the inner and outer corrugation apices of the legs 20 and 30 will be denoted as 26, 27 and 36, 37 respectively.

The machine includes die units 40 and 41 (Fig. 4), which serve to form the joints O and C respectively, and such units are mounted on the surface of a large base plate 42 supported on legs 43. The motive and main control units 44 and 45 of the machine are disposed beneath the plate 42.

The die units 40 and 41 are provided with die shoes 46 and 47 (Figs. 5 and 10), which serve as mounting means for several of the die components of their respective units. The former shoe 46 is rigidly secured to the base plate 42, while the shoe 47 carries keys 48 which engage in longitudinal keyways 49 in the plate 42. Thus, the shoe 47 and remaining portions of the unit 41, as will presently be more apparent, are adjustable to any desired fixed position relative to the unit 40. This permits the machine to be adjusted to form ribbons R of any length. For example, in Fig. 4 the unit 41 is positioned to form short water tube sections, which later may be assembled into an automobile heater core.

The shoe 47 of the unit 41 carries a lower or fixed jig 50, which is suitably serrated, as indicated by the numeral 51, to receive the lower leg 30 of the ribbon R in the first step of the operation. The shoe 47 is grooved transversely to form slide bearings 52 for receiving laterally movable jigs 53. Referring momentarily to the fixed unit 40 (Fig. 6) it will be observed that it is supplied

25

30

35

40

45

50

55

with a similar fixed jig 50a and identical laterally movable jigs 53a.

After the leg 30 of the ribbon is manually placed on the jigs 50, 50a, as shown in Fig. 4, 5 the jig pairs 53, 53a are brought together simultaneously to cover and hold the terminal portions of the ribbon leg 30 (Fig. 10). The mechanism for effecting this movement consists of a pair of shafts 54, 54a, rotatably carried in depending 10 bearing brackets 55 beneath the plate 42. Pairs of levers 56 are secured to each shaft, and they project upward through suitable slots 42a and 53b in the overlying bed plate and die shoe structures, and enter holes 57, 57a in the movable 15 jigs 53, 53a. The shafts are operated by a pedal 58 which carries a link 59, which link in turn is connected to levers 61 on the shafts 54, 54a. It will be apparent that when the pedal 58 is depressed, the levers 56 will be moved toward 20 the median line of the machine, and accordingly the accompanying jig pairs 53, 53a will be brought into abutting relation upon the lower ribbon leg 30. The shafts 54, 54a are supplied 25 with a third set of levers 62 (Fig. 6) which are formed with hook extremities 62a for receiving the ends of a tension spring 63. This arrangement provides for spring return of the jigs 53, 53a to the open position of Figs. 5 and 6 when the pedal 58 is released.

After the jig pairs 53, 53a are closed upon the ribbon, a bending die 60 on the unit 40 is manually operated to bend the ribbon upon its medial portion about the end face of the jigs 53 and to 30 superimpose the legs 20 and 30 in such manner that the flattened extremity 21 is positioned immediately above the extremity 31 in the other unit 40. The manually operated bending die 60 is formed with projecting knuckles 65 carrying 35 hinge pins 66, 67 (Figs. 5 and 10) which are rotatably received in bearings 68 in the shoe 47. The pin 66 projects to the front of the machine, where it is formed with a handle portion 69. The die 60 is also supplied with a projecting light 40 weight grid 70 which supports the ribbon leg 20 before the bending operation (Fig. 1). It will be observed that the die 60 is formed with transverse serrations 60a which match the corrugations 19 of the ribbon.

The unit 40 is provided with an upper or holding jig 71 which, in the subsequent and final manual operation, is brought into the position shown in Fig. 10, where it covers the end of the ribbon leg 20. This jig consists of a block which 50 is secured to an arm 72 (Fig. 6) which in turn is secured to a control shaft 73. A handle 74 on the arm 72 permits the operator to swing jig 71 into position on the ribbon leg 20, and additionally to actuate the shaft 73 which, as will 55 presently be explained, actuates the controls for the automatic cycle of bending operations.

The motive unit 44 includes a cam carriage 76, which is carried for longitudinal sliding movement in a pair of depending rectilinear bearings 65 71, 78, which bearings are secured beneath the base plate 42. An air cylinder 80 is secured to the right hand leg 43, and its piston rod 81 is connected to the extremity of the carriage 76 by a suitable fitting 82. The operation of the piston 70 80a of the cylinder is controlled by a valve unit 83, which is secured to the left hand leg 43 (Fig. 9). The valve unit is supplied with a control lever 84 which operates suitable valve instrumentalities (not shown) for connecting a high 75 pressure air line 85 to either the right or left

hand piston chamber through pipes 86, 87 respectively.

The active or left hand stroke of the piston 80a is instigated through clockwise movement of the valve lever 84, which lever is operated by the 5 closing movement of the jig arm 72 through an intermediate lever system (Fig. 9). The control shaft 73, which is rotatably mounted in bearings 88, carries a collar 89 on its left hand extremity in which a finger 90 is secured. The base plate 10 42 is slotted at 92 to receive a lever 93, which is pivotally mounted in a stud 94 in an adjacent bearing 95. The upper end of the lever 93 receives the bifurcated end of a pawl 96 which is pivotally carried on a stud 97. The pawl is 15 formed with an angular cam surface 100 on its free extremity. The end of the lever 93 is rounded, as indicated by the numeral 98, so that the pawl may be freely raised from the position shown in Fig. 9. The lower end of the lever is connected to a clevis 99 by a pivot pin 101, and the clevis in turn is connected to a curved portion 84a of the valve arm 84 by a connecting rod 102. It will now be apparent that when the shaft 73 is rocked by the arm 72, the finger 90 engages the cam surface 100 of the pawl 96, thus causing a partial counter-clockwise rotation of the lever 93, and the resultant movement of the lever 84 to the full line position of Fig. 9.

As the cam carriage 76 nears the end of its movement to the left, a plate 104 on its extremity strikes the control lever 84 and restores it to its first position. This reverses the air cylinder operation, and the carriage is immediately 35 returned to its starting position.

A pedestal 105 is secured to the carriage 76, and its upper portion extends through a longitudinal slot 106 in the base plate 42. The upper surface 107 of the pedestal is serrated transversely to receive a forming head 108, which head is provided with complementary serrations 109. Screws 111 secure the head 108 in position, and it will be understood that the pedestal is provided with numerous tapped holes so that the head may be 40 moved to various positions.

Secured to the head 108 are a pair of projecting cams 112, a spaced single cam 113, and a medially disposed rectilinear hammer 114. Referring to Figs. 5 and 10, it will be seen that the bending die 60 and jig 50 carry opposed crimping dies 115 and 116 respectively. These dies are loosely mounted at their extremities in slides 115a, 116a respectively, which slides are secured to the die 60 and die shoe 47 respectively. It 50 will be seen in Fig. 11 that as the carriage 76 moves to the left, the cams 112, 113 thrust the dies 115, 116 toward each other to effect a flattening of the outer sides of the corrugations 19a and the convergence of the crests thereof. Immediately after this action, the hammer die 114 strikes the angular faces of the dies 115, 116 and restores them to their original positions. The hammer then strikes the corrugations 19a and flattens them to complete the header C (Fig. 12). 60 During this operation, the lower cams enter clearance slots 118 in the jig block 50.

Secured to the carriage are cams 120, 121 (Fig. 4) which engage movable elements for forming the header joint O. The cam 120 is formed with two spaced transverse lobes 122, 123, while the cam 121 is formed with a lobe 124 and an abutment 125. A bell crank 126 is operated by the cam 120, and it is pivotally mounted on a stud 127, which stud is carried by a bearing bracket 75

128 on the plate 42. One arm 129 of the bell crank 126 depends through a slot 126a in the plate 42, and its terminal 129a receives a pawl 130 which is pivotally mounted on a stud 131. 5 The pawl is formed with an angular surface 130a, which contacts the terminal 129a when the pawl is engaged from the left. The remaining arm 133 of the bell crank 126 is formed with a rectilinear terminal 133a, to which is secured a plate-like die 134 and a cam 135. A spring 132 retains the bell crank in its open position. 10 A bearing 136 is secured to the lower side of the plate 42, and it is slotted to receive a lever 137, which lever is mounted on a pivot pin 138. 15 The upper arm of the lever 137 projects through the slot 126a, and its terminal is notched as indicated by the numeral 139. The notched end of the lever enters a slotted head 140, where it engages a transverse pin 141 which is secured in 20 the head (Figs. 4 and 12). The head is formed with gibbs 142, which are received in spaced slides 142a secured to the plate 42 (Fig. 7). A pair of wedge-like cams 140a project from the head 140. 25 The die structure, which cooperates with the bell crank 126 and head mechanism, consists of a die block 144 (Figs. 7 and 10) which normally rests on the base plate 42, but which may be lifted vertically against the end faces of the shoe 46 and fixed jig 50a. Guide plates 145 secured 30 to the jig 50a serve to position the block 144 loosely against the end faces. A hinged die element 146 is formed with a cylindrical terminal 147, which is received in a complementary socket 148 in the block 144. The upper end of the element 146 is provided with an angular extension 151 which projects over the surface 144a of the block 144. Spaced cam lobes 150 are formed on the extension 151. A compression spring 146a normally retains the element 146 in an open position, as shown in Fig. 10. 35

In operation, during the left hand or active stroke of the carriage 76, the lobe 122 of cam 120 engages the pawl 130 of the bell crank 126 to initiate the automatic cycle of bending operations. As the bell crank is rotated, the die 134 thereon engages the projecting extremity 21 of the ribbon leg 20 and bends it downward upon the end face of the jig pairs 53a. The underlying extremity 31 of the ribbon leg 30, which rests upon the die extension 151, is next engaged, and its terminal 34 is turned upward, with the forward edge of the extension 151 acting as a fulcrum. The hinged die element 146 is properly positioned during this operation by the cam 135 (Fig. 10).

As the cam lobe 122 passes out of contact, the bell crank opens slightly, as shown in Fig. 11, and as the cam 135 passes the cam lobe 150 of the hinged die element 146, the element is swung 50 inward, and the ribbon terminal 34 is accordingly contacted and bent into an acute angle. The succeeding lobe 123 of cam 120 next engages the bell crank and repeats the described movement, so that the terminal is flattened upon the 55 underlying ribbon joint sections.

The abutment 125 of the cam 121 in the succeeding operation strikes the lever 137 and swings it clockwise, thus causing the accompanying head 140 to be moved rapidly to the right. During 70 this movement the cams 140a of the head engage under and raise the die block 144, so that the joint structure is bent upon itself, as shown in Fig. 12. The forward surface of the head, as indicated by the numeral 140b, strikes the raised 75 block 144 almost immediately, and the impact is

sufficiently severe to flatten the joint in a tight leak-proof structure.

The control lever 84 of the air cylinder is tripped immediately after the last described operation, and the carriage is thereupon reversed and caused to move toward its starting position. During reverse movement, the lobe 124 of cam 121 engages the end of the lever 137 and moves it and the accompanying block 140 to their initial positions. Simultaneously, a pawl 155, mounted 10 on the head 108, engages a stud 156 (Fig. 10) on the bending die 60 of the unit 41 and automatically opens the die. The pedal 58 is now released to open the jig pairs 53, 53a, and the completed water tube ribbon is removed from 15 the machine.

Various safety devices are incorporated in the machine structure to prevent premature operation of the automatic instrumentalities, which might endanger the operator or cause damage 20 to the dies. It will be observed in Figs. 8 and 9 that the shaft 54 of the pedal mechanism carries an arm 160, which arm swings into an obstructive position against the lever 93 when the jig pairs are in their open position. Thus, the 25 arm 72, which starts the automatic operation, cannot be moved downward, and accordingly the control lever 84 of the air cylinder cannot be operated unless the jig pairs 53, 53a are closed.

The control lever 84, after being manually 30 closed, is firmly held against opening movement during the active stroke by a safety mechanism 161 (Figs. 6 and 7). This mechanism consists of a bell crank 162 which is mounted for pivotal movement on a bearing 163 beneath the plate 35 42. The bell crank is a two-part structure formed of arms 164, 165 having a common pivot pin 166 and united for limited relative movement by a pin and slot connection 167. An interposed spring 168 retains the arms in spaced relation. The 40 lower arm 165 carries a cam roller 170, which is engageable by a cam 171 secured to the side of the carriage 76. The remaining arm 164 is provided with an insert 172. The control shaft carries an arm 173 having a projecting finger 174 45 which is so proportioned that when the control lever 84 is closed, the finger enters a slot 176 in the base plate 42. In moving forward, the carriage cam 171 engages the roller 170, and swings the bell crank upward so that the insert 172 of the arm 164 engages the finger 174 and thus holds the shaft 73 against displacement. The spring connection between the arms 164, 165 absorbs 50 the shock of the cam impact, and prevents damage to the mechanism.

Similarly, the motive unit may not be operated unless the bending die 60 of the unit 41 is properly closed. This safety device 175 is shown in Figs. 5 and 13, and it comprises a plunger 186 mounted for transverse movement in a slide 177 on the shoe 41. A cam 178 is secured to the adjacent portion of the shaft 73, and it is formed with a lobe 179. The proximate end of the plunger 186 is supplied with a pawl 181, which is pivoted thereto as indicated by the numeral 182. The plunger carries a spring 183 which engages a pin 184, and thus constantly urges the plunger to the right. When the shaft 73 is rotated by manual operation of the control arm 72, the cam moves the plunger to the right, and, assuming the bending die 60 has been carelessly left in an open position, the left hand end 180 of the plunger immediately engages the die, and the operator is unable to complete the closing operation. When the die is properly closed, the plunger end 180 finds no opposition to the cam operated move- 75

ment, and it is first thrust to the left in a detector movement, and then, as the cam lobe 179 passes the pawl 181, the plunger is permitted to spring back into an unobtrusive position.

5. From the foregoing description, it will be understood that the machine of the present invention permits of the rapid formation of a length of radiator core ribbon into a continuous, folded, and joined unit, with the folds or joints at each 10 end of the section being made as substantially a single operation. In this respect, the present invention simplifies the work of making up the ribbons, and is therefore an advance over the prior art, as typified by machines such as those 15 shown in the J. M. Fedders Patent No. 1,226,490, patented May 15, 1917, or in my own prior Patent, No. 2,102,573, patented December 14, 1937. My improvements therefore in part comprise the provision of the necessary ribbon bending, holding, 20 and forming elements into a unitary machine assembly, with the provision of instrumentalities which insure and enforce their actuation in a proper sequence to convert the discrete length into a core unit without removing the work from 25 the machine, or employing two separate machines. These improvements, together with others defining the novel features of my invention, I shall now set forth in more detail in the appended claims, it being understood, of course, 30 that such claims are not intended to be restricted to the specific elements herein described by way of illustration, but to include such modifications and variations as are within the principles hereof.

35 I claim:

1. A forming mechanism for radiator ribbons, including jig means adapted to receive a length of radiator ribbon to be formed, movable holding means for folding the ribbon upon itself and 40 to hold the ribbon in such folded position, means for holding the free ends of the ribbon in juxtaposition, die means for bending and joining the free ends of the ribbon in an interlocking joint, other die means associated with said movable 45 holding means for forming and flattening the folded portion of the ribbon, movable means for actuating both of said die means simultaneously, and control means for enforcing the operation 50 of the bending, holding, and die means as sequential operations.

2. A forming mechanism for radiator ribbons comprising a base, a die unit on the base having movable die elements for uniting the ends of a ribbon in an interlocking joint, a second die unit 55 mounted on the base in spaced relation to said first unit and having movable die elements adapted to form a closed end joint in the ribbon, bending means on said last die unit for folding the ribbon upon itself, jig means on said first unit 60 for receiving and holding the free ends of the folded ribbon in juxtaposition, automatic means for operating the movable die elements of both units simultaneously, and control means for enforcing the operation of the bending, holding, and die means as sequential operations.

3. A forming mechanism for radiator ribbons comprising a base, a die unit on the base having movable die elements for uniting the ends of a ribbon in an interlocking joint, a second die unit mounted on the base in spaced relation to 70 said first unit and having movable die elements adapted to form a closed end joint in a ribbon, bending means on said last die unit for folding a ribbon upon itself, jig means on the first unit

for receiving and holding the free ends of the folded ribbon in juxtaposition, automatic means for operating the movable die elements of both units simultaneously, control means for said automatic means operatively connected to said 80 jig means, and means conditioning said control means for operation, said last named means being controlled by operation of said bending means.

4. A forming mechanism for radiator ribbons 10 comprising a base having secured thereon a pair of spaced die units each having a plurality of movable joint forming die elements, bending means on one unit for folding a ribbon upon itself, jig means on the remaining unit for receiving and holding the free ends of the folded ribbon in juxtaposition, a cam carriage, means beneath the base for mounting the carriage for sliding movement, power means for reciprocating 15 said carriage, arms secured to the carriage for operating said movable die elements, and control means for said power means associated with said jig means.

5. A forming mechanism for radiator ribbons 20 comprising a base having secured thereon a pair of spaced die units each having a plurality of movable joint forming die elements, manually operable bending means on one unit for folding a ribbon upon itself, movable jig means on the remaining unit for receiving and holding the free ends of the folded ribbon in juxtaposition in the dies thereof, cam means for operating said die elements simultaneously, power means for motivating said cam means, a control lever for 25 said power means, and a mechanism operated by and during movement of said jig means for actuating said control lever.

6. A forming mechanism for radiator ribbons 30 comprising a base having secured thereon a pair of spaced die units each having a plurality of joint forming die elements, a hinged manually operable die on one unit for folding a ribbon upon itself, jig means on the remaining unit for receiving and holding the free ends of the folded ribbon in juxtaposition in the dies thereof, a cam carriage, means beneath the base for mounting the carriage for sliding movement, cams secured to the carriage for operating said movable die elements, fluid actuated means for reciprocating 35 said carriage, a control lever for said fluid actuated means connected for operation in one direction by said jig means, and said lever being movable in a reverse direction by engagement of said carriage therewith.

7. A forming mechanism for radiator ribbons 40 comprising a base having secured thereon a pair of spaced die units each having a plurality of movable joint forming die elements, bending means on one unit for folding a ribbon upon itself, jig means on the remaining unit for receiving and holding the free ends of the folded ribbon in juxtaposition, a cam carriage, means beneath the base for mounting the carriage for sliding movement, power means for reciprocating said carriage, cams secured to the carriage for operating said movable die elements, hammers operated by the carriage for impacting the joints after formation by the dies, and control means for said power means associated with said jig 45 means.

8. A forming mechanism for radiator ribbons 50 comprising a base having secured thereon a pair of spaced die units each having a plurality of movable joint forming die elements, pedal oper- 55

ated jigs on each unit for positioning one leg of a ribbon, a manually operable bending die on one unit for folding the remaining leg upon the first leg, manually movable jig means on the remaining unit for holding the free end of the folded leg in juxtaposition on the end of the first leg, cam means for operating said die elements simultaneously, power means for motivating the

cam means, a control instrumentality for said power means operated by said manually operable jig means, and detector means organized with said pedal operated jigs and said manually operable bending die for forestalling operation of said control instrumentality when such elements are not in operative position.

STANISLAUS PRZYBOROWSKI.
